UNITED STATES PATENT OFFICE.

BEN LOTH, OF CINCINNATI, OHIO.

AEROPLANE SAFETY DEVICE.

Application filed March 17, 1926. Serial No. 95,260.

The invention relates to safety devices particularly intended to be utilized in combination with means which are described in my application, Serial Number 56,290, filed 5 September 14, 1925, Patent No. 1,584,876 granted May 18th, 1926, on similar appliances, to decrease the velocity at which an aeroplane will fall toward the earth.

The objects of the inventions are to provide simple, efficient, economical and durable means adapted to maintain the equilibrium of an aeroplane, equipped with spread wings or similar attachments, during its descent to earth; and to provide means whereby a 15 weight, as the engine of the aeroplane or other object, may be quickly and conveniently lowered below said aeroplane.

With the foregoing and other objects in view, which will appear apparent as the description proceeds, the invention resides in certain novel features, the combination, arrangement of the parts and in the details of the construction, as will be more fully hereinafter described and claimed.

25 In the drawings:

Fig. 1 is a bottom view taken in an upward vertical direction of an aeroplane equipped with the invention and shown in operative position during the downward descent with the wings in open relation;

Fig. 2 is a section taken on a line corresponding to 2-2 in Fig. 1;

Fig. 3 is a plan view of one wing in spread position and showing the aeroplane in parts broken away;

Fig. 4 is the same as Fig. 3, but showing the wing in folded position;

Fig. 5 is a section taken on a line corresponding to 5-5 in Fig. 4;

Fig. 6 is a section taken on a line corresponding to 6-6 in Fig. 3; and

Fig. 7 is a section taken on a line corresponding to 7-7 in Fig. 5.

The invention is exemplified on aeroplane or heavier than air machine 1 having usual upper and lower planes 2 and 3 suitably secured to body 4. The folding wings 5, 6, 7 and 8, respectively, have their inner edges 9, 10, 11 and 12 secured in close contact with the adjacent sides of body 4 of the aeroplane. Suitable means are employed for maintaining the wings in spread position, irrespective of the air pressure. The covering 13

of the wings preferably consists of very thin and light weight material which has sufficient tensile strength to withstand the strains to which it is subjected.

55 The hollow tubes 14 have their inner ends pivotally connected with the sides of the body of the aeroplane and are suitably secured to the covering 13. The tubes are made of extremely light weight material, as aluminum. The outer ends of the tubes are curved downwardly so that when the wings are in spread position a convexo-concave 60 form 15 is represented by the wings and the bottom 16 of the aeroplane, whereby as the aeroplane falls toward the earth the air pressure within the concave side of form 15 considerably decreases the velocity at which the 65 aeroplane travels, when not equipped with the open wings.

70 Suitable means are provided for quickly and conveniently enabling the operator of the aeroplane to spread the wings. The preferred means comprise a spring operated 75 rotatable drum adapted to wind ropes or lines 17 fixed to the outer ends of outer tubes 18 of the respective wings, whereby by simple operative means the wings are caused to 80 spread from the position shown in Fig. 4 to the position shown in Fig. 3. This form of the device, however, is fully described in the above mentioned application for a 85 patent.

85 As heretofore explained, when the wings are in spread position the falling aeroplane descends gradually, therefore the necessity of lowering the center of gravity of the complete unit 1 becomes very important for the 90 purpose of maintaining the equilibrium of the aeroplane and to prevent the currents of air from turning it with the upper side 19 downwardly. To accomplish this object, I provide bottom 16 of the aeroplane with 95 trap-door 20 upon which is mounted suitable heavy object 21. Pivotally connected, as shown in Fig. 7, by pin 22, to each outer end 23 of outer tubes or rods 18 is arm 24 adapted to remain in the horizontal position, beneath 100 tube 18, shown in Fig. 5, during the period that the wings are in folded position, whereby the apparatus is unadapted to interfere with the regular and usual operation of 105 flight of the aeroplane. To further facilitate a neat and desirable storage of the wings,

if desired, properly positioned recesses may be made longitudinally of body 4 to receive the folded wings 5, 6, 7 and 8, and arms 24.

The trap-door 20 is maintained in closed position by bolt 25 slidably mounted in staples 27 and 26, respectively, secured in the upper sides 28 and 29, respectively, of bottom 16, of the aeroplane, and trap-door 20.

The ends 30 of lines 31 are connected with inner ends 32 of arms 24. The outer ends 33 of the lines are connected with object 21, whereby simply removing bolt 25 from engagement with staple 26 permits the object 21 to fall, by gravitation, through opening 34 thereby pivoting arms 24 to the position shown in Fig. 2.

It is very important to provide convenient means whereby bolt 25 may be removed from engagement with staple 26 to permit object 21 and arms 24 to drop to the position shown in Fig. 2, during the operation of the spreading of the wings, or immediately thereafter. For this purpose the staff 35 is slidably mounted in hole 36 in bottom 16 of the aeroplane. Attached to the lower end of the staff is cable 37 having connection with end 38 of bolt 25, whereby downward movement of the staff by the foot of the operator of the aeroplane slides the bolt from engagement with staples 26, thereby permitting the trap-door to open, whereby the force of falling object 21 forces arms 24 downwardly and thereby lowers the heavy object a considerable distance below the aeroplane. It is important that object 21 is of sufficient weight to lower the center of gravity of the unit 1' far enough below the aeroplane to prevent the ordinary currents of air from turning the aeroplane upside down during the gradual descent.

If desired the staff 35 may be connected with the means employed to spread the wings, so that the same operation of the operator of the aeroplane may effect spreading the wings and lowering object 21. Furthermore, it is preferred that staff 35 is positioned near the feet of the operator of the aeroplane so that he can quickly and conveniently permit the trap-door to fall.

By the use of the means herein described an aeroplane may be caused to gently float to the earth without injury to the aeroplane or its occupants, whereas in the past, if for any reason the engine of a flying aeroplane failed to actuate, the only chance to bring the aeroplane safely to the earth was to glide at a very high rate of velocity and land on a smooth and level surface. For this reason, the danger of personal injury is great while flying in an aeroplane, not equipped with a safety appliance. But persons may fly with safety provided my invention, in combination with the wings 5, 6, 7, and 8, is attached thereto simply because if the aeroplane engine fails it is merely necessary for the operator to

press a button, lever or staff for actuating mechanism for unfolding the wings and dropping object 21, and the aeroplane and the persons therein will float to the earth without mishap.

The object 21, as exemplified herein, is merely a heavy object, as iron, but it is understood that any suitable article, thing, device or mechanism may be utilized for the purpose. For instance, by arranging the usual engine of the aeroplane with flexible connections and detachable supports, the engine may be substituted for object 21, or in certain types or kinds of aeroplanes, or other heavier than air machines, the fuel or gasoline storage tanks may be substituted for object 21, or in bombing aeroplanes the bombs may be substituted for object 21, and in freight carrying aeroplanes, which soon may be universally used, the freight may be substituted for object 21.

To further facilitate in forming a concave surface under surface of form 15, as shown in dotted lines in Fig. 2, the bottom 16 of the aeroplane may be curved at 38. Furthermore, the tubes may be of slightly flexible material, whereby object 21 is adapted to bend the wings downwardly, although of course, when the weight of the object is removed from the wings, the tubes will regain their original shape so as to not interfere with the wheels of the usual carriage (not shown) contacting the ground.

It is apparent that I have invented a thoroughly practical device for the purposes intended and which may be advantageously utilized for preventing the destruction of falling aeroplanes as well as saving the lives of the occupants.

While I have chosen to illustrate certain forms of the preferred construction of the invention by the herein drawings and the explanations, it is understood that certain changes may be made, and I desire that it is thoroughly understood that the invention resides in the combination, arrangement of the parts and in the details of the construction, as hereinafter claimed. For example the construction shown and described of the object and the trap-door, together with the means for permitting the object and the arms to be lowered is merely one simple form of the parts for accomplishing the desired purpose. The important thing, among others, is the use of a relatively heavy object by which the center of the gravity of the unit 1' may be lowered to enable the wings to be practical and dependable to perform the intended functions without the likelihood of the aeroplane turning over or permitting the air pressure, within the concave portion of the form 15, to escape therefrom entirely. I have found by practical tests that the use of object 21 in the form of a heavy weight will maintain the equilib-

rium of a falling aeroplane which is equipped with wings which, when open, are parachute or umbrel-like shaped.

What I claim as new and desire to secure by Letters Patent, is:

1. The combination with an aeroplane having downwardly curved wings capable of being opened and closed, of a trap-door in said bottom, a relatively heavy object mounted on said door, arms pivotally mounted on said wings, lines connecting said arms and said object, and means to permit said door to open for dropping said object below said aeroplane and pivoting said arms downwardly, substantially as and for the purposes specified.

2. The combination with an aeroplane having wings adapted to be opened, of arms

pivots connected with the outer ends of said wings, lines connected with said arms, a relatively heavy object connected with said lines, means to retain said object adjacent said aeroplane during the normal operations of said aeroplane, and means to lower said object below said aeroplane in cooperation with said wings in open position, substantially as and for the purposes specified.

3. The combination with an aeroplane having wings capable of being opened and closed, of a heavy object, arms connected with said heavy object and the outer ends of said wings, and means to permit said heavy object to be lowered below said aeroplane whereby said aeroplane is adapted to remain right side up during the descent.

BEN LOTH.
